UNITED STATES PATENT OFFICE.

ALFRED P. SEIDELL, OF BLOOMFIELD, NEW JERSEY, ASSIGNOR TO ORANGE LIGHTING FIXTURE MANUFACTURING CO., A CORPORATION OF NEW JERSEY.

DESIGN FOR A LIGHTING-FIXTURE BACKPLATE OR ARTICLE OF ANALOGOUS NATURE.

Application filed February 10, 1928. Serial No. 25,360. Term of patent 7 years.

To all whom it may concern:

Be it known that I, ALFRED P. SEIDELL, a citizen of the United States, and a resident of Bloomfield, county of Essex, and State of New Jersey, have invented a new, original, and ornamental Design for a Lighting-Fixture Backplate or Article of Analogous Nature, of which the following is a specification, reference being had to the drawing, substantially as shown, forming a part hereof.

In the drawing:

Figure 1 is a front elevational view of the lighting fixture backplate or article of analogous nature; and

Figure 2 is a diagrammatic side outline view of the same.

I claim:

The ornamental design for a lighting fixture backplate or article of analogous nature, of which the following is a specification, reference being had to the drawing, substantially as shown.

ALFRED P. SEIDELL.
